UNITED STATES PATENT OFFICE.

LEWIS J. MORGAN, OF SYRACUSE, NEW YORK.

LATCH FOR AUTOMOBILE DOORS AND THE LIKE.

Original application filed February 12, 1922, Serial No. 536,592. Divided and this application filed October 3, 1924. Serial No. 741,472.

This invention relates to latches for doors and has for its object a particularly simple and efficient mechanism for doors as automobile doors by which the handle can be adjusted into different angular positions to conform to the incline or angle of the door and the curve of the outer surface of the door.

This latch is of the same general type as that shown in my application, Sr. No. 536,592, filed February 12, 1922 of which this application is a division.

The invention consists in the novel features and in the combinations and constructions hereinafter set forth and claimed.

In describing this invention, reference is had to the accompanying drawings in which like characters designate corresponding parts in all the views.

Figure 1 is a sectional view illustrating my door latch and the contiguous portion of the door.

Figure 2 is an elevation looking to the left in Figure 1.

Figure 3 is a face view of the latch shown in Figure 1, the door being omitted and the shank or shaft of the handle being in section.

Figures 4 and 5 are respectively a side elevation and an edge view of the ball of the socket joint and the cam pivoted thereto.

Figure 6 is a plan view looking downwardly in Figure 4, the contiguous part of the latch casing being shown.

Figure 7 is an enlarged sectional view on the line of 7-7, Figure 3.

As is well known to those skilled in the art, the doors of automobiles are slightly inclined out of a vertical plane and also the doors and especially the outer surfaces thereof curve or bulge to conform to the lines of the car body.

This invention relates to means whereby the handle of the latch member can be readily positioned at any desired angle irrespective of the incline of the door and the latch casing and of the curve or bulge of the outer surface of the door.

This door latch mechanism comprises a casing, a latch member movable in the casing and operating means comprising a handle mounted to have a universal adjusting action relatively to the casing, the handle being connected to a ball mounted in the casing to have a universal joint adjusting

movement and this ball having a cam extending radially outwardly therefrom and pivoted thereto on an axis extending transversely of the shank or shaft of the handle, the cam coacting with the latch. Also the cam and the latch member having coacting faces which are socketed one in the other at a point remote from the pivot of the cam so that the cam remains in practically the same relation to the latch member in all adjustments of the ball in its socket.

1 designates the casing which may be of any suitable form, size and construction, it being usually formed of opposing walls of sheet metal formed with suitable guides for a latch member 2. This latch member is here shown as a bolt reciprocally movable in the casing between the opposing walls thereof and pressed in one direction by a spring 3, the latch member extending through the edge of the casing and having a latch portion 4 for coacting with the keeper plate on the door frame.

5 is a ball mounted in the casing, the casing being shaped to form a socket in which the ball has a universal movement. As here shown, the casing is formed with flanges 6 flaring around circular holes in the walls of the casings, which flanges form a socket.

7 is the handle which has the shaft 8 extending through the door 9 from the outer side thereof and being connected to the ball. As here shown, one of these parts so connected and usually the ball is provided with an axial passage 10 which is square or polygonal in cross section and the shank 8 which is angular or square extends into said passage.

11 is the cam extending outwardly from the ball, the cam being pivoted at 12 to the ball to have a lateral movement relatively to the door or rather to remain stationary in so far as lateral movement is concerned in any adjustment of the ball to conform to the angle of the shank 8 of the handle 7. The pivot 12 extends in a direction crosswise of the shaft 8. The cam coacts with an angular arm 13 extending from the bolt or latch member 2 and this arm 13 and the cam are provided with interfitting engaging faces at 14 or faces which socket one within the other. Usually one of these parts as the arm 13 is formed with a concave face and the cam with a convex or spherical face 15 remote from the pivot of the cam so that dur-

ing the movement of the ball to conform to the angle of the shank 8. Upon the initial installation of the handle, the cam is held from rocking movement with the ball by the 5 interfitting faces at 14.

In operation, the casing 1 is attached to the inner side of the door or the frame thereof and the hole for the shank 8 of the handle can be located in any desired position or angle to conform to the incline and curve of the door, different curves and inclines being shown by full and broken lines in Figures 10 1 and 2. The shaft can then be inserted in the axial hole of the ball irrespective of the 15 incline or bulge of the door. The shank 8 or handle 7 is held from axial displacement in any well known manner or as shown in my pending application Sr. No. 536,592, of 20 which this application is a division.

20 What I claim is:

1. A door latch mechanism comprising a casing formed with a socket, a latch member movable in the casing, and operating means comprising a cam coacting with the latch, a 25 ball mounted in the socket, a connection between the ball and the cam to permit adjusting movement of the ball in the socket relatively to the cam and the latch member.

2. A door latch mechanism comprising a 30 casing formed with a socket, a latch member movable in the casing, and operating means comprising a rocking cam, a ball mounted in the socket, the cam being pivoted to the ball and a handle having a shaft connected to the ball.

3. A door latch mechanism comprising a 35 casing formed with a socket, a latch member movable in the casing, and operating means comprising a cam coacting with the latch member, a ball mounted in the socket, the cam being pivoted to the ball, and a handle having a shaft connected to the ball; the pivot of the cam extending in a direction transversely of the axis of the shaft.

45 4. A door latch mechanism comprising a casing formed with a socket, a latch member movable in the casing and operating means comprising a shaft, a rocking cam coacting

with the latch member, a ball mounted in the 50 socket, the cam being pivoted to the ball and the ball being mounted on the shaft having a handle thereon, the ball being formed with a non-circular passage for receiving the shaft.

5. A door latch mechanism comprising a 55 casing formed with a socket, a latch member movable in the casing, and operating means comprising a rocking cam coacting with the latch member, a ball mounted in the socket, the cam being pivoted to the ball; a handle 60 for the shaft connected to the ball, the ball being formed with an axially extending passage for receiving the shaft.

6. A door latch mechanism comprising a 65 casing formed with a socket, a latch member movable in the casing, and operating means comprising a cam coacting with the latch, a ball mounted in the socket, a connection between the ball and the cam to permit adjusting 70 movement of the ball in the socket relatively to the cam and the latch member, the latch member and the cam having their coacting faces, one socketed in the other, to hold the cam engaged with the latch member during the adjusting movement of the ball 75 to the handle.

7. A door latch mechanism comprising a 80 casing formed with a socket, a latch member movable in the casing, and operating means comprising a cam coacting with the latch member, a ball mounted in the socket, the cam being pivoted to the ball, and a handle having a shaft connected to the ball, the pivot of the cam extending in a direction 85 transversely of the axis of the shaft, the latch member and the cam having their coacting faces, one socketed in the other, to hold the cam engaged with the latch member during the adjusting movement of the ball to the handle.

In testimony whereof, I have hereunto signed my name at Syracuse, in the County of Onondaga and State of New York, this 26th day of September, 1924.

LEWIS J. MORGAN.
